UNITED STATES PATENT OFFICE.

JACOB SIEBER, OF LONDON, ENGLAND, ASSIGNOR TO CHARLES THOMAS EVERIST, OF FOREST HILL, LONDON, ENGLAND.

CARBURETOR FOR INTERNAL-COMBUSTION ENGINES.

Application filed June 2, 1924, Serial No. 717,434, and in Switzerland June 12, 1923.

The present invention relates to carburetors for internal combustion engines. The main feature of the improved carburetor is the provision of means for admitting water 5 into the mixing chamber at a point between the rotary mixer and the throttle. Various other subsidiary features will be hereinafter described with reference to the accompanying drawings which illustrate by way of example one construction of the carburetor.

Fig. 1 is a vertical section through the carburetor. Fig. 2 is a top view of the valve device controlling the fuel admission, Fig. 3 is an elevation corresponding to Fig. 1.

Referring to Figs. 1 to 3, the tubular casting 101 of the carburetor is provided in its lower portion 102 with a choke valve 104 rotatably mounted at 105, and is provided at its upper or discharge end 103 with a 20 throttle valve 106 turnably mounted at 107 for controlling the discharge of the combustible mixture.

The carburetor may, as usual, be connected by means of its upper flange to the induction 25 tube of the engine. The shafts 105 and 107 of the choke and throttle valves 104 and 106 are operatively connected by arms 108 and 109 coupled by a connecting rod 110. The proportions of the cross sectional areas of 30 the air passage and the combustible fuel passage may if desired be varied by varying the effective lengths of the arms 108 and 109 for which purpose each arm is provided with a number of holes for receiving the 35 corresponding ends of the connecting rod 110. Between the choke and throttle valves 104 and 106 is rotatably mounted between two cross rods 112 and 113 a fan-like rotary mixer 114 carried by a vertical shaft 115.

40 The water is admitted through a conical check valve 116 arranged at a point above the rotary mixer 114, that is, at a point between the rotary mixer and the throttle 106. The water admission valve is con-

45 structed as a spring actuated check valve, a spring 118 surrounding the valve stem 119 and acting upon a disc 122 held by a nut 120. The water is admitted from a supply 50 pipe 124 which is fixed to the casing 125 by means of a screw cap 126, and passes into the valve casing through a small hole 123 and small holes (not shown) in the disc 122.

55 The valve 116 has only a very small lift relatively to the valve seat 121 and is actuated by the suction produced by the engine

acting upon a disc 117 fixed to an internal projection of the valve. It will be understood that at very low speed no, or very little, water will be admitted, whilst at high speed of the engine the suction acting upon 60 the disc 117 will lift the valve and allow water to drop upon the rotary mixer 114. As a rule, the water will be atomized before reaching the rotary mixer. Between the rotary mixer 114 and the choke valve 104 65 is arranged a liquid fuel supply preferably in such a manner as to cause the fuel jet to issue through the inclined orifice 134 of the nozzle 133 in an oblique direction as indicated by the chain line in Fig. 1. The 70 needle valve 141 regulating the fuel supply to the nozzle 133 is held in the closed position by a spring 142 mounted in the tubular extension 129 of the casing 127. In the casing 127 which communicates with the nozzle 75 by a tubular extension 128 having a longitudinal bore 130 is rotatably mounted a cam 138 the shaft 139 of which carries a lever 145 coupled by a connecting rod 111 to the connecting rod 110. The cam 138 acts directly upon the inner end of the needle valve 141 as shown in Fig. 2 and is held in position by a spring 137 held by a cap 136 screwed into the end of the chamber 135. 80 The tubular part 128 is fixed to a tubular extension 132 by means of a nut 131. A stop valve 144 adapted to be actuated by means of a rod 151 and lever 150 is provided in the fuel admission pipe 143 leading to the tubular extension 129. The proportion of 85 the fuel admission may again be varied by altering the position of the connecting rod 111 for which purpose the lever 145 is provided with a number of holes. It will be understood that the three valves 141, 104 and 106 are simultaneously operated by the same 90 operating part acting for instance upon the lever 145.

The carburetor may, if preferred, be used without a constant level tank and may be 100 used for almost any kind of fuel, for instance, benzine, petrol, alcohol or acetylene. When using petrol, it is advisable to use an admixture of benzine until the petrol is 105 sufficiently heated. The proportion of water may vary within wide limits and is, for instance, higher when using acetylene than when using petrol.

The carburetor is particularly suitable 110 for heavy cars and lorries. With both

throttle and choke valves fully open at full speed the suction and the carburetor will be sufficient to revolve the fan at a very high speed whereby complete atomization of the fuel and the water may be attained. It will be seen that all parts are very easily accessible and that the carburetor may be very easily cleaned.

I claim:

- 10 1. A carburetor comprising in combination a mixing chamber, a rotary mixer located within said mixing chamber, an air inlet in said mixing chamber adapted to direct air onto said rotary mixer, a fuel inlet on said mixing chamber adapted to direct fuel unobstructedly onto said rotary mixer, a water inlet adapted to direct water unobstructedly onto said rotary mixer and a mixture outlet, said air, fuel and water inlets being adapted to direct air, fuel and water simultaneously onto said rotary mixer.
  - 15
  - 20

2. A carburetor comprising in combination a mixing chamber, a rotary mixer located within said mixing chamber, an air inlet in said mixing chamber adapted to direct air onto said rotary mixer, a fuel inlet on said mixing chamber arranged between said rotary mixer and said air inlet and adapted to direct fuel unobstructedly onto said rotary mixer, a mixture outlet on said mixing chamber, and a water inlet arranged between said rotary mixer and said mixture outlet and adapted to direct water unobstructedly onto said rotary mixer, said air, fuel and water inlets being adapted to direct air, fuel and water simultaneously onto said rotary mixer.

3. A carburetor comprising in combination
40 a mixing chamber, a rotary mixer
located within said mixing chamber, an air
inlet in said mixing chamber adapted to
direct air onto said rotary mixer, a fuel
inlet on said mixing chamber adapted to
45 direct fuel unobstructedly onto said rotary
mixer, a throttle valve, and a water inlet
arranged between said rotary mixer and
said throttle valve and adapted to direct
water unobstructedly onto said rotary
50 mixer, said air, fuel and water inlets being
adapted to direct air, fuel and water simulta-
neously onto said rotary mixer.

4. A carburetor comprising in combination a mixing chamber, a rotary mixer located within said mixing chamber, an air inlet in said mixing chamber adapted to direct air onto said rotary mixer, a fuel inlet on said mixing chamber adapted to direct fuel unobstructedly onto said rotary mixer, a water inlet adapted to direct water unobstructedly onto said rotary mixer, said air, fuel and water inlets being adapted to

direct air, fuel and water simultaneously onto said rotary mixer, a throttle valve, said water inlet being arranged between said rotary mixer and said throttle valve, a needle valve controlling said fuel inlet and a cam actuating said needle valve. 65

5. A carburetor comprising in combination a mixing chamber, a rotary mixer located within said mixing chamber, an air inlet in said mixing chamber adapted to direct air onto said rotary mixer, a fuel inlet on said mixing chamber adapted to direct fuel unobstructedly onto said rotary mixer, a water inlet adapted to direct water unobstructedly onto said rotary mixer, said air, fuel and water inlets being adapted to direct air, fuel and water simultaneously onto said rotary mixer, a throttle valve, said water inlet being arranged between said rotary mixer and said throttle valve, and said fuel inlet being adapted to cause the fuel jet to issue below the rotary mixer and in a direction oblique to the axis of rotation thereof. 80 85 90 95 100

6. A carburetor comprising in combination a mixing chamber, a rotary mixer located within said mixing chamber, an air inlet in said mixing chamber adapted to direct air onto said rotary mixer, a fuel inlet on said mixing chamber adapted to direct fuel unobstructedly onto said rotary mixer, a water inlet adapted to direct water unobstructedly onto said rotary mixer, said air, fuel and water inlets being adapted to direct air, fuel and water simultaneously onto said rotary mixer, a throttle valve, said water inlet being arranged between said rotary mixer and said throttle valve, air and fuel admission valves, and operating means interconnecting said air, fuel and throttle valves.

7. A carburetor comprising in combination a mixing chamber, a choke valve in said mixing chamber, a throttle valve in said mixing chamber, a rotary mixer arranged between said choke valve and said throttle valve, an air inlet in said mixing chamber adapted to direct air onto said rotary mixer, a liquid fuel nozzle arranged between the choke valve and the rotary mixer and adapted to direct fuel unobstructedly onto said rotary mixer in an oblique direction, a water inlet adapted to direct water unobstructedly onto said rotary mixer, and a water admission valve arranged between the rotary mixer and the throttle valve, said air and water inlets and said liquid fuel nozzle being adapted to direct air, fuel and water simultaneously onto said rotary mixer. 120

In testimony wherof I have hereunto set my hand.

JACOB SIEBER.
